[57] **CLAIM**

The ornamental design for turbo ceiling fan, as shown
and described.

DESCRIPTION

FIG. 1 is a side elevational view of a turbo ceiling fan
showing my new design, the opposite and adjacent sides
being mirror images of that shown, and the broken-line
showing of mounting hardware being for illustrative
purposes only and forming no part of the claimed de-
sign.

FIG. 2 is a top plan view thereof;

FIG. 3 is a bottom plan view thereof; and

FIG. 4 is a bottom perspective view thereof.

FIG. 1

FIG. 2

FIG. 3

FIG. 4
